UNITED STATES PATENT OFFICE.

SAMUEL PRICE WETHERILL, JR., AND JOHN PRICE WETHERILL, JR., OF PHILADELPHIA, PENNSYLVANIA, ASSIGNEES, BY DIRECT AND MESNE ASSIGNMENTS, TO WETHERILL FINISHED CASTINGS COMPANY, OF PHILADELPHIA, PENNSYLVANIA, A CORPORATION OF PENNSYLVANIA.

PNEUMATIC CASTING APPARATUS.

1,029,565.

Specification of Letters Patent.

Patented June 11, 1912.

Application filed September 8, 1906, Serial No. 333,817. Renewed November 3, 1911. Serial No. 658,419.

To all whom it may concern:

Be it known that we, SAMUEL PRICE WETHERILL, Jr., and JOHN PRICE WETHERILL, Jr., citizens of the United States, 5 both residing at Philadelphia, State of Pennsylvania, have invented certain new and useful Improvements in Pneumatic Casting Apparatus; and we do hereby declare the following to be a full, clear, and 10 exact description of the invention, such as will enable others skilled in the art to which it appertains to make and use the same.

Our invention relates to certain new and useful improvements in the casting of metal, 15 and particularly to improvements in apparatus designed for that purpose.

In carrying out our invention, we subject the metal to be used in the casting operation to a sufficient degree of heat to 20 bring it into a state of fluidity appropriate to the uses of the apparatus. For this purpose, we place the metal, which may conveniently consist of an alloy (such as an aluminum alloy, or the like) fusible at 25 a relatively low heat, in a melting pot, which may be of cast-iron, having a refractory lining and which is conveniently heated externally by means of products of combustion from a gas burner, or other 30 source of fuel supply operating within a furnace, within which the melting pot is suspended.

From the cover of the melting pot depends a refractory dip tube, whose lower 35 end terminates at a point near the bottom of the pot, so as to be well below the surface of the molten metal, and whose upper portion is provided with a nozzle having a conical recess, for the reception of the corresponding conical gate of a two part mold, 40 which in the casting operation is clamped in place, in any suitable manner.

In order to force the molten metal into the mold, we make use of compressed air, 45 admitted to the upper surface of the metal in the melting pot, and we take special precaution to prevent the entering jet, or jets, of compressed air from channelling into, or penetrating, the body of the molten metal. 50 To this end, we so locate the jet, or jets, that they will enter or be deflected laterally in the space above the metal, instead of impinging directly upon the surface of the metal and tending to force their way into 55 the latter.

In one of the modifications of our invention, we not only force the metal from the melting pot into the mold, but, instead of venting the mold into the outer air, we connect its interior with a vacuum tank or 60 pump and vent it through the same. The vacuum is brought into operation immediately before, or simultaneously with, the admission of the compressed air into the melting pot. Furthermore, to prevent any 65 possible chilling of the metal in the nozzle of the dip pipe, we make use of a suitable burner for keeping the said nozzle heated to a non-chilling temperature during the temporary periods of removal of the mold 70 during a series of casting operations.

In the accompanying drawings we have illustrated suitable embodiments of our improvements, so as to make apparent the essential features of novelty contained 75 therein.

In the drawings, Figure 1 represents a side elevation and partial section of one form of such apparatus. Fig. 2 represents a like view of a modification thereof, with the mold removed, and with the heating devices for the dip-pipe nozzle in place. Fig. 3 represents another form of dip-pipe nozzle in its relation to the dip-pipe and to the cover of the melting pot. 80 85

Similar letters of reference indicate similar parts.

Referring to the drawings, A indicates supporting standards for the heating furnace, which may conveniently consist of an outer shell B having a lining of refractory material a, and a cover b from which is suspended the melting pot C. The furnace may be readily heated by means of the burner D, supplied with a combustible mixture from the gas pipe E and compressed air pipe F, having suitable regulating or controlling cocks, as shown. The products of combustion enter the interior of the furnace through the perforated distributing plate c, and escape through the exit flue G. 90 95 100

The melting pot C, which is usually of cast-iron, is provided with a lining of a liquid or pasty refractory material, applied thereto, of substantially the same coefficient of expansibility as the cast-iron body portion, for the purpose of protecting the metal against the corrosive action of the fused metal, and to protect the metal itself 105 110

from admixture with the elements of the cast-iron, which otherwise might seriously interfere with the availability of many suitable alloys, for the purposes intended. The melting pot is provided with a metal cover *e*, removably secured in place by screw bolts and nuts, as shown, or otherwise, and through this cover extends a thimble *I* intermediate between the air compression pipe *J* and the jet mouthpiece *f*, which latter is attached to the lower screw-threaded end of the thimble. It will be noted that the jets of the mouthpiece *f* discharge laterally into the melting pot, instead of downwardly, the bottom of the jet mouthpiece serving as a baffle plate for this purpose. The in-rushing compressed air entering through these jets does not tend, therefore, to force itself under the surface of the metal, and thereby to channel, chill and oxidize it, but is distributed uniformly over the upper surface of the metal in the pot and exerts a uniform pressure thereon appropriate to the uses of the invention.

The dip-pipe *H* is formed of fire clay, or other refractory and stable material inert to the metal to be cast, and, in order to support it properly, and at the same time to provide means for clamping the mold in alinement with it, it is provided with a nozzle of metal. This nozzle may be screw-threaded into the cover, as illustrated in Figs. 1 and 2; or, as illustrated in Fig. 3, it is made up of two parts, *g*, *h*, separately connected by means of screws *i*. The upper one of these plates is preferably inserted flush with the surface of the cover *e* and is removably secured therein by means of the screws *n*. It is provided with a conical bore *m* for co-operation with the corresponding conical gate of the casting mold. The lower part *h* of the nozzle is provided with a conical recess for the reception of packing material *s* of pasty consistency, and which will set and harden so as to hold the dip-pipe *H* in place, and to make this union the more complete, we preferably provide the upper end of the dip-pipe *H* with a number of recesses on its outer periphery, as illustrated in Fig. 3, within which packing material enters.

The casting mold is made up of two separable counterparts. In Fig. 1, we have shown one of these counterparts *K*, with its conical gate *t*. The channel or hollow interior of the gate communicates with the casting cavity *v* of the mold and the casting cavity is vented by the side channels shown, which communicate with a common exit or venting channel *w*.

In the form of our invention shown in Fig. 2, it is contemplated to employ a mold which will vent into the open air and which will be clamped in place by the screw *L* passing through the screw-threaded aper-

ture of the cross-head *M* of a yoke *N* secured to the frame of the apparatus. In the form of the invention shown in Fig. 1, however, the mold is vented through the conduit *P* of a vacuum pump, so as to facilitate and improve the casting operation by the joint action of pressure applied to the top of the metal in the melting pot and a vacuum formed in the interior of the mold. The hollow clamping screw *R* passing through the cross-head *M* of the yoke *N* is provided at its lower end with a clamping head *T*, having a conical mouthpiece for the reception of the conical vent projection *z* of the mold, and for the reception of the elastic or flexible packing ring *x*.

In Fig. 2 we have also illustrated the means which we prefer to employ for maintaining a non-chilling temperature in the nozzle of the dip-pipe, during the intervals between successive casting operations, so as to prevent the chilling of the metal therein, and so as to permit any metal that has not entered the mold to pass back into the melting pot. It will be noted that the heating device referred to is a burner *l* supplied with a mixture of gas and air from the gas-pipe *E* and compressed air pipe *F*, the branches taken off for this purpose being provided with regulable cut-off cocks or valves, as shown. The burner *l* and its mixing chamber *y* are adapted to swing side-wise out of the way of the mold, when the latter is inserted in place. In order not to complicate the illustration, we have not shown this burner in connection with the form of our apparatus illustrated in Fig. 1; it will be understood, however, that we contemplate using it in that form of apparatus also.

The mode of operation of the invention will be apparent. The metal to be cast is inserted in the melting pot and the cover *e* with its adjuncts, is attached thereto airtight. The metal is then brought to a molten condition, and when at a temperature suitable for casting, the mold is clamped in place. Compressed air is then admitted to the upper surface of the metal through the pipe *J*, thimble *I* and jet mouthpiece *f*, whereupon the metal is forced upwardly through the dip-pipe *H* into the mold, the mold being vented, either into the open air, or by means of the vacuum conduit, operated simultaneously with, or in the instant preceding the admission of the compressed air to the melting pot. When the casting is thus effected, the operating cocks of the air compression pipe and vacuum pipe are closed, the clamping devices of the mold are released, and the mold is removed and disassembled. The burner *l* is then swung around into place to heat the nozzle of the dip-pipe for the purposes hereinbefore stated.

Having thus described our invention, what we claim is:—

1. A casting apparatus, comprising a melting pot adapted to serve as a containing reservoir for the molten casting metal, an air-tight cover for the pot, a dip-pipe depending from and removable through the cover and whose lower end opens near the bottom of the pot, a casting mold separate from the cover and having a gate in alignment with the upper end of the dip-pipe, and means for transferring the molten casting metal from the melting pot into the mold; substantially as described.

15. 2. A casting apparatus, comprising a melting pot adapted to serve as a containing reservoir for the molten casting metal, an air-tight cover for the pot, a dip-pipe depending from and removable through the cover and whose lower end opens near the bottom of the pot, a casting mold separate from the cover and having a gate in alignment with the upper end of the dip-pipe, and a fluid pressure conduit opening into the pot above the level of the casting metal therein; substantially as described.

30. 3. A casting apparatus, comprising a melting pot adapted to serve as a containing reservoir for the molten casting metal, an air-tight cover for the pot, a dip-pipe depending from and removable through the cover and whose lower end opens near the bottom of the pot, a casting mold separate from the cover and having a gate in alignment with the upper end of the dip-pipe, and a fluid pressure conduit opening into the pot above the level of the casting metal therein, and having a side delivery, thereby avoiding penetration of the entering air jet 40 or jets into the metal; substantially as described.

45. 4. A casting apparatus, comprising a melting pot adapted to serve as a containing reservoir for the molten casting metal, an air-tight cover for the pot, a dip-pipe depending from the cover and whose lower end opens near the bottom of the pot, a casting mold having a gate in alignment with the upper end of the dip-pipe, means 50 for releasably holding the mold in place, means for directing a heating flame upon the upper open end of the dip-pipe when the mold is not in place, and a fluid pressure conduit opening into the pot above the level of the casting metal therein; substantially as described.

55. 5. A casting apparatus, comprising a melting pot adapted to serve as a containing reservoir for the molten casting metal, an air-tight cover for the pot, a dip-pipe depending from the cover and whose lower end opens near the bottom of the pot, a casting mold having a gate in alignment with

the upper end of the dip-pipe, means for releasably holding the mold in place, means 65 for directing a heating flame upon the upper end of the dip-pipe when the mold is not in place, said means consisting of an air pipe and a gas pipe discharging into a mixing chamber from which extends a burner pipe, 70 the said air and gas pipes being mounted to swing into and out of position, and a fluid pressure conduit opening into the pot above the level of the casting metal therein; substantially as described.

75. 6. In a metal casting apparatus, a melting pot adapted to serve as a containing reservoir for the molten casting metal, an air-tight cover for the pot, a dip-pipe having at its upper end a nozzle by which it is suspended from the cover, said nozzle having a conical recess in its upper surface, a casting mold having a conical gate fitting into the said conical recess, means for releasably clamping the mold in place, and a fluid pressure conduit opening into the pot above the level of the casting metal therein; substantially as described.

80. 7. In a metal casting apparatus, a melting pot adapted to serve as a containing 90 reservoir for the molten casting metal, an air-tight cover for the pot, a dip-pipe, consisting of a main body portion of refractory material and a nozzle by which it is suspended from the cover, said nozzle being 95 made up of an upper portion having a recess in alignment with the bore of the dip-pipe, a lower portion surrounding the upper end of the refractory body portion and having a recess for the reception of a packing 100 cement, together with means for uniting the said upper and lower portions, a casting mold having a gate fitting the nozzle, and a fluid pressure conduit opening into the pot 105 above the level of the casting metal therein; substantially as described.

85. 8. In a metal casting apparatus, the combination with a melting pot, of an air-tight cover, having a dip-pipe consisting of a main body portion of refractory material 110 and a nozzle provided with a receiving recess for a mold gate, and a fluid pressure conduit entering the melting pot through the intermediacy of a screw-threaded thimble which passes through the cover, and 115 which carries at its lower end a jet-distributing mouthpiece; substantially as described.

In testimony whereof we affix our signatures, in presence of two witnesses.
